C. F. GREGG

RUG CLEANING MACHINE

Filed August 15, 1924

UNITED STATES PATENT OFFICE.

CHARLES F. GREGG, OF INDIANAPOLIS, INDIANA.

RUG-CLEANING MACHINE.

Application filed August 15, 1924. Serial No. 732,248.

My invention relates to improvements in fabric cleaning machines and is particularly designed for cleaning rugs and other heavy fabrics.

5 One of the objects of my invention is to provide a machine in which the rug or other articles to be cleaned may be thoroughly drenched with cleaning fluid and at the same time scoured without wrinkling or folding 10 the rug and in which the cleansing fluid may be reclaimed.

For the purpose of disclosing my invention I have illustrated one embodiment thereof in the accompanying drawings in which,

15 Fig. 1 is a side elevation of a machine embodying my invention;

Fig. 2 is a front end view thereof, and

Fig. 3 is a detail section on the line 3—3 of Fig. 1.

20 In the embodiment of the machine illustrated I provide a suitable supporting frame 1 comprising the two side bars 2 which may be formed of channel iron or the like and which are provided at suitable intervals with 25 supporting legs 3. These side bars, on their inner faces, at suitable intervals, are provided with bearing brackets 4, in which are mounted rollers 5. Mounted to reciprocate on the rollers of the main frame is a carrier 30 frame 6 comprising the side members preferably formed of angle irons, the horizontal members 7 of which are provided on their under faces with rails 8 co-operating with the grooved rollers 5 of the main frame.

35 The side rails of the carrier frame are secured together at their ends by means of cross braces 9 and disposed at suitable intervals along the carrier frame, being journaled in the vertical members 10 of the side members of the carrier frame, are transversely extending shafts 11 carrying at their opposite ends, to rotate therewith, eccentric cams 12. These shafts are adapted to be rotated simultaneously and to this end each 40 shaft is provided at its center with a worm wheel 13, each operated by a worm 14. The worms 14 are mounted on a longitudinally extending shaft 15 journaled in the cross braces 9 and provided at its front end with an operating wheel 16 for rotating the shaft.

The rug supporting frame 17 preferably comprises a pair of side rails 18 connected at their ends by cross rails 19 and mounted upon this frame is a series of spaced longitudinal bars 20 which in turn have mounted 55 thereon a wire mesh 21, this arrangement forming a support for the rugs to be cleaned and at the same time forms a drainage surface to permit the passage therethrough of the cleaning fluid. The wire mesh is provided at suitable intervals with small upwardly extending pins 22 which retain the article to be cleaned on the platform or rug frame 17.

60 Mounted on the under side of the carrier frame 6 is a drip pan 23, the sides of which are provided with horizontal flanges 24 for securing to the horizontal side members 7. The forward end of this pan is closed and the bottom inclines downwardly from the 70 front to the rear of the carrier frame, the pan being of the same length as the carrier frame.

65 Mounted in the main frame and below the carrier frame pan is a drain pan 25 which, at all times will receive the drainage from the pan 23 and has its bottom sloping toward a central point 26 at which point there is provided an outlet pipe 27 preferably leading 75 to a clarifying tank.

80 Above the carrier frame there is provided a housing 28 closed at its rear end and having at its front an opening just sufficiently large to accommodate the passage of the carrier frame. Within this housing and at 85 the forward end thereof is mounted a rotatable cleaning brush 29 preferably adapted to rotate in the direction indicated by the arrow and immediately above the brush 29 there is a spray pipe 30 extending transversely of the housing and adapted to deliver the cleaning fluid immediately above and slightly in front of the cleaning brush. The fluid is delivered to this spray pipe by a suitable supply pipe 31 and, if desired, 90 additional spray pipes 32 may be extended across the housing at suitable intervals. At the forward portion of the housing and to the rear of the brush 29 there is preferably 95 provided a baffle plate 33.

In operation the carrier platform is run out of the housing to the forward end of the frame, either by hand or a suitable motor operated reciprocating mechanism. The rug 5 to be cleaned is unrolled on the wire mesh in a perfectly flat position being held against displacement by the pins 22. After the rug has been placed in position the height of the carrier frame is adjusted to bring the 10 rug into proper contact with the brush 29, by means of the worms and gears 13 and 14. After suitable adjustment, the cleansing fluid is admitted through the spray pipe and the carrier platform or frame moved 15 into the housing and beneath the brush. As the rug passes beneath the brush it is thoroughly drenched with the cleansing fluid and brushed so that all dirt is removed and the cleansing fluid drains through the carrier 20 platform into the drip pan 23 and out the rear end of this drip pan into the drain pan 25 from whence it is drained to a suitable settling tank.

The rug may be reciprocated beneath the 25 brush and cleansing fluid as often as is necessary to thoroughly clean the same.

I claim as my invention:

1. A machine for cleaning carpets comprising a flat foraminous reciprocal bed 30 capable of receiving the carpet to be cleaned flatwise, an open bottomed housing capable of receiving the entire bed having an opening at one end through which the bed may be projected into and out of the housing, a rotary brush mounted in said housing above the path of movement of said bed, means within the housing above the path of movement of said bed and delivering cleaning fluid on the top of the carpet to be cleaned as said bed 35 moves within said housing and an end delivering collecting pan beneath and movable with said bed.

2. A machine for cleaning carpets comprising a flat foraminous reciprocal bed 40 capable of receiving the carpet to be cleaned flatwise, an open bottomed housing capable of receiving the entire bed having an opening at one end through which the bed may be projected into and out of the housing, a rotary brush mounted in said housing above the path of movement of said bed, means within said housing above the path of movement of said bed for delivering cleaning fluid 45 on the top of the carpet to be cleaned as said bed moves within said housing and a collecting pan beneath and movable with said bed.

3. A machine for cleaning carpets comprising a flat foraminous reciprocal bed capable 50 of receiving the carpet to be cleaned flatwise, an open bottomed housing capable of receiving the entire bed having an opening at one end through which the bed may be projected into and out of the housing, a rotary brush mounted in said housing above 55 the path of movement of said bed, means

within said housing above the path of movement of said bed for delivering cleaning fluid on top of the carpet to be cleaned as said bed moves within said housing, means for obtaining a relative adjustment between said bed and brush and an end delivering collecting pan beneath and movable with said bed. 70

4. A machine for cleaning carpets comprising a flat foraminous reciprocal bed capable 75 of receiving the carpet to be cleaned flatwise, an open bottomed housing capable of receiving the entire bed having an opening at one end through which the bed may be projected into and out of the housing, a rotary brush mounted in said housing above the path of movement of said bed, means within said housing above the path of movement of said bed for delivering cleaning fluid on top of the carpet to be cleaned as 80 said bed moves within said housing, a collecting pan beneath and movable with said bed and means for obtaining a relative adjustment between said bed and brush. 85

5. In a device of the character described, 90 the combination with a main frame, a housing supported thereby, a rotary brush mounted within said housing, a carrier frame reciprocable on said main frame in said housing, an article supporting flat bed foraminous frame vertically adjustably mounted on said carrier frame, means for delivering a cleaning fluid to the article to be cleaned within said housing, a fluid receiving pan mounted on and moving with said carrier frame and beneath the article carrying frame, a drainage pan arranged beneath said housing and adapted to receive the fluid from said movable pan. 95 100

6. In a device of the character described, 105 the combination with a main frame, a housing mounted on said main frame, a carrier frame reciprocable on said main frame into and out of said housing, a foraminous flat bed article supporting frame mounted on 110 said carrier frame and vertically adjustable thereon, a rotary brush within and at the forward end of said housing, means for delivering a cleaning fluid across the face of said article supporting frame said means being located adjacent to said brush, a fluid receiving pan carried by said carrier frame beneath said article supporting frame and movable therewith and a drainage pan beneath said first mentioned pan to receive the fluid therefrom. 115 120

7. In a device of the character described, 125 the combination with a main frame, of a housing mounted thereon, a rotary brush mounted at the forward end of said housing, cleaning fluid delivery nozzles arranged within said housing adjacent said brush and adapted to deliver cleaning fluid to said brush, a carrier frame reciprocably mounted on said main frame and adapted to be pro- 130

jected into and withdrawn from said housing, a foraminous flat bed article supporting frame mounted on said carrier frame and vertically adjustable thereon, a fluid receiving pan mounted on and beneath said carrier frame and movable therewith, and a drainage pan mounted on said main frame be-

neath said housing and adapted to receive the fluid from said first mentioned pan.

In witness whereof, I CHARLES F. GREGG ¹⁰ have hereunto set my hand at Indianapolis, Indiana, this 12th day of August, A. D. one thousand nine hundred and twenty-four.

CHARLES F. GREGG.
